His atys.

UNITED STATES PATENT OFFICE.

JOHN J. DUCK, OF TOLEDO, OHIO.

LOOM-FASTENER.

1,242,533.

Specification of Letters Patent.

Patented Oct. 9, 1917.

Application filed March 23, 1917. Serial No. 156,933.

To all whom it may concern:

Be it known that I, JOHN J. DUCK, a citizen of the United States, and a resident of Toledo, in the county of Lucas and State 5 of Ohio, have invented a certain new and useful Loom-Fastener; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates to loom fasteners, and is particularly intended for holding one or more non-metallic flexible looms in place at outlet boxes.

The object of my invention is the provision of a simple and efficient means for 20 use in connection with outlet and terminal boxes, or in other places where adapted, to secure flexible insulating looms in position therein and to effectually prevent pulling 25 away of the looms from the part or device from which the wire carrying the electric current is to be insulated.

The invention is fully described in the following specification, and while, in its 30 broader aspect, it is capable of embodiment in numerous forms, a preferred embodiment thereof is illustrated in the accompanying drawings, in which—

Figure 1 is a sectional view of a wall or 35 ceiling with a loom holding outlet box embodying the invention associated therewith. Fig. 2 is an enlarged perspective view of the outlet box in inverted position with the loom fastening means associated therewith 40 and holding a loom in position, and Fig. 3 is a top or inner side perspective view of the outlet box with the wall engaging screws projecting therefrom.

Referring to the drawings, 1 designates a 45 loom outlet box, which may be provided with a plurality of loom receiving openings 2, which openings may if desired be initially closed by "knockout" blanks 3, as well

understood in the art. The loom receiving openings 2 are provided around the central 50 portion of the box 1 and are of suitable size to receive a flexible loom or insulating tube 4 through which the current carrying wire 5 is projected. 6 designates the customary fixture stud, which projects from the outer 55 side of the box substantially centrally thereof and has feet 7, which may be secured to the box by screws or bolts 8, which may also project into the portion of the wall or ceiling 9 with which the loom box 60 is associated to secure such box thereto.

The feature comprising my invention consists in securing a loom gripping plate or member 10 to the side of the box 1 to which the fixture stud 6 is attached, or to the side 65 of the box in the direction of projection of the loom therethrough. The plate 10 is of spring metal and has one or both ends projected in restricting relation to adjacent loom openings 2 and are bent outward on 70 an incline with respect to the box wall through which the openings are provided and notched to partially receive a loom when projected through one of said openings. The ends of the plate 10 form spring 75 jaws which permit an insertion of a loom in one direction through the openings 2 with which the plate is associated but prevent pulling away of the looms from the box due to the engagement of the spring 80 ends of the plate with the loom, as is apparent. It is evident that the plate 10 may be adapted to engage a loom or looms projected through any or all of the openings 85 in an outlet box, and that the harder the outward pull on a loom to withdraw it from a box opening, the harder will be the gripping action of the plate end on the loom as the size of the opening will be greater restricted by the plate end as it is drawn inward toward the same.

I wish it understood that my invention is not limited to any specific construction, arrangement or form of the parts, as it is capable of numerous modifications without 90 departing from the spirit of the claim.

Having thus described my invention, what I claim as new, and desire to secure by Letters Patent, is—

The combination with an outlet box of 5 the class described having loom receiving openings therein and a fixture stud secured to said box, of a plate of spring metal retained to the box by said stud and having a

part projecting transversely therefrom into loom gripping relation to at least one of 10 said openings and serving to prevent withdrawal of a loom from the opening.

In testimony whereof, I have hereunto signed my name to this specification.

JOHN J. DUCK.
